(57) **CLAIM**

The ornamental design for break-away appendages for mounting bracket, as shown and described.

DESCRIPTION

FIG. 1 is a top side end perspective view of break-away appendages for mounting bracket showing my new design, FIG. 2 is a side elevational view thereof, FIG. 3 is a reverse side view thereof, FIG. 4 is an end view thereof; and, FIG. 5 is a bottom plan view thereof. The broken lines shown are for illustrative purposes only and form no part of the claimed design.
